TRUSS

Henry A. French, Charlestown, N. H.

Application September 25, 1933, Serial No. 690,828

6 Claims. (Cl. 128—103)

My invention relates to improvements in trusses.

An object of my invention is to provide a truss of light weight, resilient material, having means thereon for adjustably locating the pressure pads and also means thereon for adjustably controlling the pressure exerted by the pressure pads.

Other objects and advantages of my invention will be more completely described and disclosed in the following specification, the accompanying drawing, and the appended claims.

Broadly, my invention comprises a truss frame consisting of two, or more, thin, resilient, metal bands, pivotally connected, pad-supporting members pivotally secured to the free ends of the truss frame, a hinge incorporated in one, or both, of said pad-supporting members, pressure pads secured on the pad-supporting members, an elastic band member, slidably secured on the inner surface of the resilient truss frame, the band member being fixedly secured to one of the pad-supporting members and adjustably secured to the other of the pad-supporting members, and means for securing the free end of the elastic band member, in adjusted position.

A preferred embodiment of my invention is illustrated in the accompanying drawing, in which:—

Fig. 1 is a perspective view of a truss embodying the principles of my invention.

Fig. 2 is an exterior, elevational view of one end of the truss, illustrated in Fig. 1.

Fig. 3 is an interior, elevational view of the pivotal joint in the truss frame, at the side of the truss.

Fig. 4 is a plan view of the opposite end of the truss, illustrating the hinged connection of the pad support.

Fig. 5 is an exterior, elevational view of the end of the truss, shown in Fig. 4.

Fig. 6 is a detail, sectional view on the line 6—6 of Fig. 2, illustrating the supporting means for the elastic tension band, and

Fig. 7 is a diagrammatic plan view, illustrating the truss in position on the body of a wearer.

Referring now to the drawing in detail, in which like numerals refer to like parts throughout:—

The truss frame members 1 and 2 have their ends 3 and 4 pivotally connected by means of the pin, or stud, 5. The end portion 3 of the member 1 is formed with a plurality of openings 6, which, in co-operation with the pin, or stud 5, provide for longitudinal adjustment of the members 1 and 2. The opposite end 7 of the member 1 has pivotally secured thereto, at 8, the link member

9. A pad-supporting member 10 is hingedly secured to the link member 9 by the hinge 11. The free end 12 of the truss frame member 2 has pivotally secured thereto, at 13, the pad-supporting member 14. Pressure pads 15 and 16, of any suitable resilient material, are secured to the members 10 and 14, respectively, in any suitable manner, such as rivets 17. A leg strap 18, of elastic webbing, or similar material, is secured to the members 1 and 2, as indicated in Fig. 1.

An elastic band member 19, fixedly secured at one end 20 to the pad-supporting member 10, is slidably secured on the inner surface of the members 1 and 2 by clips 21. The free end 22, (see Fig. 2), of the band member 19 is passed through the opening 23, formed in the supporting member 14, and held in place, after the desired tension is exerted on pads 15 and 16, by means of the pin 24 secured on the outside of the supporting member 14.

In operation, the truss frame is first longitudinally adjusted to fit the body and the points to be protected, by positioning the pin, or stud 5, in the proper opening 6. Further adjustment is secured by turning, or moving, the members 1 and 2, relative to each other, as indicated in Fig. 3, and by moving the members 9 and 14, relative to the members 1 and 2, respectively, as indicated in Figs. 2 and 5. When the desired adjustment has been secured, the pads 15 and 16 are pulled inwardly by pulling on the free end 22 of the elastic band member 19, until the desired pressure is obtained. The band 19 is then secured in position to maintain this pressure, by means of the pin 24.

In order to provide a smooth, flush, unbroken surface, next the body of a wearer, the members 1 and 2 are formed with recesses 25, as indicated in Fig. 6, where the clips 21 are secured on the members 1 and 2, so that the inner surface 26 of the clips 21 and the inner surface 27 of the band 19 are flush. It is to be understood that the truss, when in use, engages, or contacts, at only two points, namely, on the spine and at a point where pressure is to be applied, as shown in Fig. 7, at the two points only at 28 and 29, with a space 30 between the body and the truss.

What I claim is:—

1. A truss construction comprising, in combination, a plurality of spring band members forming in combination a U-shaped spring frame, said band members being pivotally connected for movement relative to each other, pad-supporting members pivotally secured to the free ends of

- said U-shaped frame for movement relative to the ends of said frame, pressure pads pivotally secured on said band members, an elastic tension band member fixedly secured to one of said 5 pad-supporting members and adjustably secured to the other of said pad-supporting members, and means for slidably securing said tension band member on the inner surface of said arcuate frame.
- 10 2. In a truss construction having a U-shaped resilient spring frame with free ends, a pressure pad secured on one of said free ends, a pad-supporting member pivotally secured on the other of said free ends for movement relative to the 15 said frame, a pressure pad secured on said pad-supporting member, and a tensional band member slidably secured on the inner surface of said frame and operatively connected to said pressure pads for forcing said pressure pads inwardly of said resilient frame and towards each other, substantially, as described.
- 15 3. A truss construction comprising, in combination, a U-shaped member of resilient material, a plate pivotally secured to each end of 20 said member, a cushion pad on each plate, an elastic member slidably supported on the inner surface of the U-shaped member and connected to the plates for drawing the cushion pads inwardly, and means for varying the tension of 25 the elastic member.
- 20 4. A truss construction comprising, in combination, a U-shaped member of resilient material, a hinge plate pivotally secured to each end of 25 said member, a cushion pad on each hinge plate, an elastic member slidably supported on 30 the inner surface of the U-shaped member and
- 30 connected to the said hinge plates for drawing the cushion pads inwardly, means for varying the tension of the elastic member, said means comprising an opening in one of the hinge plates, a sharp pin adjacent the opening through which 80 an end of the elastic member passes, the opposite end of the elastic member being attached to the other pad-supporting hinge plate, whereby the pressures exerted by the pads on the wearer may be varied.
- 35 5. In a truss construction, a resilient frame member having free end portions, front and rear pad-supporting members pivotally connected to the said free end portions of the resilient frame member, pressure pads on the end of said pad-supporting members, an elastic band member slidably secured on the inner surface of the resilient frame member and having one end thereof 90 fixedly secured to the front of the pivotally connected pad-supporting members and the opposite end thereof being adjustably secured to the other one of said pad-supporting members.
- 40 6. In a truss construction, a resilient spring frame member having free ends comprising a plurality of bands of resilient metal pivotally connected, front and rear pressure pads pivotally secured on the free ends of said frame, an elastic tension band located on the inner surface of the said spring frame and fixedly secured to one of the pressure pads of said frame and adjustably secured to the other pressure pad of 100 said frame, means for holding said tension band in adjusted position, and means for slidably supporting said tension band on the inner surface of said spring frame.
